UNITED STATES PATENT OFFICE.

JOHN H. GOODFELLOW, OF BUFFALO, NEW YORK, ASSIGNOR TO FRANCES LOUISE ELLIOTT, OF BUFFALO, NEW YORK.

APPARATUS FOR CLEANING BOILERS.

Application filed July 30, 1920. Serial No. 400,191.

To all whom it may concern:

Be it known that I, JOHN H. GOODFELLOW, a citizen of the United States, residing at Buffalo, in the county of Erie and State 5 of New York, have invented a new and useful Improvement in Apparatus for Cleaning Boilers, of which the following is a specification.

This invention relates to boiler tube or 10 flue cleaners of the type adapted to clean the tubes or flues of a boiler or steam generator by means of the injection of a blast of steam or other cleaning agent under pressure.

15 The objects of the invention are to provide a device for cleaning a comparatively small group of boiler flues or tubes at one time so that not sufficient soot or deposit is removed from the boiler at one time to 20 exceed the capacity of the stack to carry off the soot or deposit; also to provide an apparatus provided with means for simultaneously producing suction in some tubes and blowing other tubes by pressure; also 25 to provide in the front boiler chamber means for changing the direction of movement of the soot blown out of the tubes, so as to direct the soot toward the stack; also to provide a nozzle of improved construction for producing suction in a boiler 30 tube; also to provide a device of this kind which can be easily and quickly installed in a fire tube boiler and which requires comparatively few changes in the boiler encasement; also to provide means of improved 35 construction for maintaining the cleaner in its operative position relatively to a boiler; also to provide means for removing soot or deposits from the lower portion of the front 40 chamber of the boiler and to direct the soot or deposit upwardly into the stack; also to provide blower nozzles adapted to be positioned in the tubes which effectively operate to increase the efficiency of the boiler 45 and more fully utilize the heat of the gases and other products of combustion passing through the tubes; and to improve the construction of apparatus of this kind in other respects hereinafter specified.

50 In the accompanying drawings:—

Fig. 1 is a sectional elevation showing the front tube sheet of a horizontal boiler equipped with the improved cleaning apparatus.

Fig. 2 is a fragmentary horizontal section 55 thereof.

Fig. 3 is a detail partly in section of a pressure supply nozzle for the cleaning medium, showing the same applied to an intake pipe. 60

Fig. 4 is a side elevation partly in section of the improved apparatus in conjunction with the front end of a boiler.

Fig. 5 is a horizontal section through one 65 of the tube blower nozzles.

Fig. 6 is a side elevation partly in section of the nozzle shown in Fig. 5.

Fig. 7 is a section through one of the 70 boiler tubes and the nozzle heads taken on line 7—7, Fig 4.

Referring to the drawings, 10 designates a steam boiler or generator of the fire-tube type containing a plurality of tubes which are designated as 11. The usual stack for the discharge of smoke and waste gases is 75 designated as 12, the front header or tube-sheet of the boiler as 13, and the front boiler wall as 14, the front wall being provided with doors 14^a. A fire tube boiler of any other kind may be used in connection 80 with the tube cleaning apparatus embodying the invention.

In the embodiment illustrated, the apparatus of the present invention comprises a plurality of upright conduits or blower 85 tubes 15 and 15^a, which are adapted to be positioned adjacent the front header of the boiler, the conduits 15 being provided at their upper ends with caps or closures 16 having holes or discharge orifices which are 90 so arranged as to direct a blast of steam or other agent under pressure upwardly toward and into the stack. The conduits 15 in the construction shown, are in communication with and carry lateral pipe members 95 17 which are adapted to extend into the fire tubes 11 of the boiler and which are equipped at their discharge ends with return or redirecting nozzles 18. These nozzles 18 are preferably formed with a 100 rounded or curved head or end wall 19 and a rounded shoe or bottom portion 20 conforming to the curvature of the inside of the tube and having top walls 19^a which enclose a central chamber 20^a. The nozzles 105 are preferably further provided with upwardly and forwardly directed slits or openings 21 preferable at the sides of the

intake portion whereby steam or other cleaning agent entering the nozzle is directed forwardly from the nozzle head and diagonally of the length of the tubes. The 5 rear end of the nozzle members preferably terminates in an angular blade or edge as at 22 lying close to the bottom of the boiler tube, and the top wall inclines upwardly from this knife edge to the slits or openings 21, whereby a minimum of resistance 10 is offered to gases and other products of combustion normally passing through the tubes and soot or other material being drawn over the top of the nozzle is directed 15 upwardly in the zone of the blasts discharging from openings 21. For the purpose of holding the nozzle close to the wall of the tube and of providing supporting means for maintaining the conduits 15 and their 20 attached parts in proper position, the nozzle 18 is preferably formed with a vertical blade or fin as at 23. It is desirable that this blade be approximately of such height that the upper edge will closely fit the interior 25 of the tube, as indicated in Fig. 7, and it is also considered preferable that the blade be so shaped that a minimum resistance will be offered to the passage of the combustion products through the tubes.

30 When steam or other fluid under pressure is admitted to the nozzles 18, the same will be discharged through the discharge orifices 21 therein diagonally across the tubes as shown in Fig. 4, thereby producing a suction in the boiler tubes which will draw soot and other foreign matter out of the tubes. By blowing the steam across the pipes at a slight angle to the lengths thereof, a better cleaning of the tubes is effected 35 than by merely blowing the steam in the direction of the length of the tubes. The nozzles also have a further function of forming baffles or restrictions in the boiler tubes, which retard the flow of the products of combustion in the tubes when the nozzles 40 are not used for cleaning the tubes, and thereby increase the efficiency of the boiler.

45 The conduits or tubes 15 have mounted thereon a plurality of lateral tubes corresponding in number to the boiler tubes in any line of the nest, and any desired number of these laterals may be equipped with the return nozzles as described. It is, however, considered preferable to equip the upper tubes of a line with return nozzles and to provide lateral blower members for some of the lower boiler tubes of the line which consist of the jet nozzles 24, Fig. 4. The result of this arrangement is that the lower 50 jet nozzles will blow soot and deposit rearwardly through some of the lower boiler tubes and a suction will be created in the upper tubes, which draws soot and deposit from the rear of the boiler to the front 55 thereof. Consequently the soot and deposit

blown rearwardly in the lower boiler tubes will be drawn forwardly through the upper tubes. The discharge of steam through the orifices in the caps 16, together with the inclination given to the steam by the 60 nozzles 18, induces an upward current of fluid and solid matter at the front of the boiler toward the smoke stack, so that the direction of the material discharged from the boiler tubes will be changed in such a 65 manner that the material removed from the tubes will be readily discharged into the smoke stack.

70 For the purpose of creating a suction influence in the lower part of the chamber or space between the tube sheet 13 and the front boiler wall 14, whereby any soot or other material deposited therein may be removed during the actuation of the cleaner, 75 one or more of the conduits 15^a is equipped 80 at its lower end with an upwardly directing nozzle 25 which acts in a sleeve or shield 26 to create an upwardly directed blast in this space to suck or draw the material therein 85 up into the blast from the upper portions 90 of the cleaner, whereupon it will be carried out through the stack and removed. The sleeve or shield 26 also prevents material sucked upwardly by the nozzle 25 and shield 26 from being carried into the lower 95 boiler tubes during the cleaning operation. The sleeve or shield 26 is preferably provided with a lower bell-shaped hood 27 whereby the suction within the sleeve may 100 be exerted upon a considerable area of the boiler floor and is supported in spaced relation to the boiler casing as by legs 28 whereby soot or other sediment may be freely drawn from the boiler floor up 105 through the hood.

110 In order to maintain the blower members in position, one or more of the laterals 17 may be equipped with an adjustable stop 29 which is adapted to fit or hook over the flanged end of one of the boiler tubes, as at 30, thus preventing movement of the blowers inwardly relatively to the tubes. In order to provide against movement in the other direction, there may be provided a 115 spacing member, strut or leg 31 which is pivoted as at 32 to a clamp or similar fastening device 33 adapted to be positioned on the conduit member 15, the free end of the member 31 bearing upon the wall or door of the boiler. For purposes of further securing the apparatus in position, conduit members 15^a adjacent the sides of the boiler may be equipped with brackets 34 which may be bolted, as at 35, or otherwise 120 removably secured to the side walls of the boiler, or to a brick setting (not shown), if such a setting is used in place of the side walls shown. Each conduit 15 and the corresponding conduit 15^a, if one is used, are 125 in communication with a suitable intake 130

pipe 36 through the medium of a coupling member 36^a which permits the conduits 15 and 15^a to be adjusted laterally so that the laterals connected therewith may be properly positioned in the boiler tubes. The intake pipes 36 terminate in a common head 37 which head holds the ends of the intake pipes 36 together and which in the construction shown, extends through a hole formed 10 in a boiler door 14^a. The head preferably has a flange 38 which abuts against the inner face of the door. In order to permit access to the intake head the boiler wall is provided with a suitable door 39, which 15 in the construction shown, is detachably pivoted to the head 37. It is considered preferable that this door be pivoted at two ends so that it may swing either to the right or left in opening and with this end in 20 view, the intake pipe head 37 is provided with struck out apertured flanges or ears as at 40 and the door is formed with a pair of apertured lugs 41 at each end adapted to register with respective ears on the intake head and to be held in place by a suitable removable pin member as 42. Consequently when it is desired to open the boiler door 14^a it is only necessary to remove the hinge pins 42 and to remove the door 39, 25 after which the door 14^a may be swung open, leaving the head 37 in a stationary position with reference to the boiler.

The conduit members communicating with a common intake head are preferably connected together by means of a clamping strip 43, illustrated in Fig. 2 of the drawings, this strip preferably comprising two duplicate clamping members each provided with spaced recesses adapted to register with 30 the recesses of the other, whereby sockets 44 are provided for the reception of the conduit members. The strip members are held together by any suitable fastening means, such as bolts 45. The boiler tube cleaner is preferably built in two parts or sections, one section being provided for each half of the boiler and, in the construction shown, the two sections are preferably secured together by means of a spacing strip 45, the opposite ends of which are secured to the ends of the clamping strips 43 of each section of the tube cleaner.

Steam or other cleaning medium may be admitted to the intake tubes in any suitable manner, a nozzle 46 being shown for this purpose, see Fig. 3. This nozzle fits into the outer ends of the intake tubes, which are preferably tapered, so as to form a steam tight joint. The nozzle may be connected to a steam line and may be inserted in any one of the steam intake tubes whereby the boiler tubes in communication therewith may be blown out.

In order to facilitate the assembling of 45 the apparatus in, or removal from a boiler,

the members 15^a equipped with the lower upturned blower nozzles are provided at their lower ends with suitable pipe unions 47, whereby the blower members may be disconnected and removed without disturbing the 70 nozzles 25 or the sleeve 26. Below each union 47 a fitting 50 is provided which has a suitable turn post 51 adjustably secured therein. By means of these turn posts the flue cleaning apparatus may be adjustably 75 supported with reference to the boiler wall.

It will be seen that an apparatus is provided which can be readily fitted to any type of fire-tube boiler without any special skill and with only one change or alteration in 80 the boiler, that is the cutting of a hole in the front boiler wall or the front door to permit the intake tube head to extend through the hole.

In the operation of the device, when steam or other cleaning agent under pressure is supplied to one of the intake pipes, an upwardly directed blast will be produced in the space between the front boiler header and the front boiler wall 14 by the orifices 90 in the caps 16. At the same time the lowermost laterals will inject blasts of the cleaning agent into the lower tubes, while the return nozzles on the laterals in the upper tubes act to draw the deposit through the 95 upper tubes and blow it into the blast through the stack. One of the intake pipes of each half of the cleaner is connected with an upwardly directed nozzle 25 and when steam is admitted to such an intake pipe, 100 soot and deposit in the bottom of the space between the header and front boiler wall will be drawn upwardly and discharged into the stack.

While the apparatus described is primarily 105 intended to be used for cleaning a comparatively small number of tubes at a time, yet it will be understood that it is not intended to limit the invention to such use, since a number of features of this invention 110 can be used equally well in connection with apparatus intended for blowing out all of the boiler tubes at a time.

I claim as my invention:—

1. The combination with a boiler including fire tubes and a boiler door, of cleaning apparatus comprising a plurality of sets of nozzles, each set of nozzles being adapted to act on a group of tubes, an intake pipe for each set of nozzles, the outer ends 120 of said intake pipes terminating adjacent to each other, and a head for positioning said outer ends of said intake pipes and which extends through a hole in said door.

2. The combination with a boiler including fire tubes and a boiler door, of cleaning apparatus comprising a plurality of sets of nozzles, each set of nozzles being adapted to act on a group of tubes, an intake pipe for each set of nozzles, the outer ends 125 of

of said intake pipes terminating adjacent to each other, a head for positioning said outer ends of said intake pipes and which extends through a hole in said door, and a flange on said head which abuts against said door.

3. The combination with a boiler including fire tubes and a boiler door, of cleaning apparatus comprising a plurality of sets of nozzles, each set of nozzles being adapted to act on a group of tubes, an intake pipe for each set of nozzles, the outer ends of said intake pipes terminating adjacent to each other, a head for positioning said outer ends of said intake pipes and which extends through a hole in said door, and a second door detachably secured to said head for closing the ends of said intake pipes.

4. The combination with a fire tube boiler having a boiler door, of a cleaning apparatus comprising a plurality of sets of blowers, each set of blowers being adapted to direct a cleaning agent into a group of tubes, an intake pipe for each set of blowers, the outer ends of said intake pipes terminating in adjacency and extending through said boiler door, said outer ends of said intake pipes being formed to receive a discharge nozzle, whereby a soot removing agent may be introduced into the respective intake pipes.

5. In a boiler tube cleaner, in combination with a steam boiler, a conduit member adapted to be positioned adjacent a boiler header, a blast nozzle on the upper end of said conduit and adapted to discharge toward the stack, a blower nozzle connected to the lower part of the conduit, whereby an upwardly directed auxiliary blast may be created, lateral pipe members extending from said conduit into the boiler tubes, and suction and blower nozzles on said lateral pipe members, whereby the tubes may be

placed under blower and suction influences.

6. In combination with a fire tube boiler, a pipe adapted to be inserted into one of the tubes of said boiler for discharging fluid under pressure to said tube, a nozzle on the end of said pipe which extends into the boiler tube, said nozzle having discharge slits directed upwardly and toward the pipe to which it is connected for discharging a film of fluid at an inclination across said tube and an upper wall which inclines upwardly from the inner end of said nozzle to said discharge openings.

7. In a boiler tube cleaner, a nozzle adapted to be positioned in a boiler tube adjacent to one end thereof and having an orifice adapted to discharge cleaning fluid toward said end of said boiler tube and thereby induce in said tube a flow of fluid toward said end, said nozzle having a bottom conforming to the floor of the tube in which it is placed, and an upper portion tapering forwardly and downwardly to a substantial knife edge.

8. In a boiler tube cleaner, a nozzle adapted to be positioned in a boiler tube adjacent to one end thereof and having an orifice adapted to discharge cleaning fluid toward said end of said boiler tube and thereby induce in said tube a flow of fluid toward said end, said nozzle having a bottom conforming to the floor of the tube in which it is placed, an upper portion tapering forwardly and downwardly to a substantial knife edge, and an upwardly extending fin engaging the upper wall of the boiler tube and confining said nozzle to the lower part of the tube.

Witness my hand this 26th day of July, 1920.

JOHN H. GOODFELLOW.
